Primary Examiner — Mitchell I. Siegel(74) *Attorney, Agent, or Firm* — McNair Law Firm, P.A.;
Douglas L. Lineberry(57) **CLAIM**

The ornamental design for a golf ball retriever, as shown and described.

DESCRIPTION

FIG. 1 is a front perspective view of the golf ball retriever shown with an unclaimed golf ball and unclaimed fragmented handle;

FIG. 2 is a back perspective view of the golf ball retriever; FIG. 3 is a bottom perspective view of the golf ball retriever; FIG. 4 is a side elevation view of the golf ball retriever; FIG. 5 is a top plan view of the golf ball retriever; and, FIG. 6 is a bottom plan view of the golf ball retriever.

The broken line showing of the golf ball and fragmented shaft on FIG. 1 is for illustrative purposes only and forms no part of the claimed design.

1 Claim, 3 Drawing Sheets(56)
